(57) **CLAIM**

The ornamental design for a garage light, as shown and described.

DESCRIPTION

FIG. 1 is a top plan view of a garage light showing my new design;

FIG. 2 is a left side view thereof;

FIG. 3 is a right side view thereof;

FIG. 4 is a front view thereof;

FIG. 5 is a back view thereof;

FIG. 6 is a bottom plan view thereof;

FIG. 7 is a perspective view thereof; and,

FIG. 8 is a perspective view of folded state.

The broken lines shown in the drawings depict portions of the garage light in which the design is embodied that form no part of the claimed design.
